UNITED STATES PATENT OFFICE

HARRY F. WATERS, OF ST. LOUIS, MISSOURI, ASSIGNOR TO MAGNETIC ORGAN ACTION COMPANY, OF UNIVERSITY CITY, MISSOURI, A CORPORATION OF MISSOURI

VALVE ACTION FOR PIPE ORGANS

Application filed December 21, 1927. Serial No. 241,511.

This invention relates generally to pipe organs, and particularly to an improved valve action therefor, the predominant object of the invention being to produce an improved valve action for pipe organs which is so constructed and arranged with relation to the associated parts of the organ that the length of the passageways through which air passes from the wind chest of the organ to the associated pipes thereof is greatly reduced. In other words, the main object of the invention is to produce an improved valve action which, because of its construction, may be arranged in very close proximity to the orifice in the toe of the associated pipe through which air passes to cause said pipe to speak.

Prior to this invention, the valve actions of most pipe organs with which I am familiar were located a considerable distance from the toes of the pipes with which said valve actions were respectively associated, and as a result of this arrangement, it was necessary to provide relatively long passageways through which the air would pass from the wind chest of the organ to the pipes thereof. A number of distinct disadvantages arose out of this arrangement, one of the more important ones being that a loss of air pressure was felt due to excessive friction between the moving bodies of air and the walls of the relatively long air passageways. In addition to this, the action of the organ was rendered relatively slow because of the time consumed for the air to pass through the extended passageways.

My improved valve action is so constructed that it may be located in very close proximity to the toe of the associated pipe, whereby the need for relatively long air passageways is eliminated.

Another object of my invention is to produce a relatively simple valve construction which will permit of the valve mechanism being easily and readily dismantled for the purpose of repairing same, or for any other purpose.

Figure 1 is a fragmentary section showing my improved valve action associated

with a portion of the wind chest and a portion of a pipe of an organ;

Figure 2 is a cross-section on line 2—2 of Fig. 1;

Figure 3 is a fragmentary vertical section of the lower portion of a pipe showing my improved valve action located within said pipe;

Figure 4 is a fragmentary vertical section of another form of my invention in accordance with which the valve mechanism is supported by the top wall of the wind chest of the organ;

Figure 5 is a modified form of the arrangement shown in Fig. 4;

Figure 6 is a fragmentary section showing a form of my invention in accordance with which the valve seat is secured to the associated pipe;

Figure 7 is a view of a construction similar to that shown in Fig. 6 but which provides for securing the entire valve mechanism to the lower end of the associated pipe.

In Fig. 1 of the drawings, A designates the wind chest of a pipe organ and B is the top wall thereof which is provided with an opening C. Secured by suitable fastening devices to the top wall B of the wind chest A at the top face thereof and in position immediately above the opening C is a pipe block 1, said pipe block being adapted to overlap the marginal edge of the opening C and is provided with a centrally arranged downwardly-extended portion 2 which is provided with screw threads at its circumference and is extended into the opening C. The pipe block 1 is provided with a centrally arranged passageway 3 formed therethrough, and 4 designates a downwardly-extended annular portion which provides a valve seat at its lower end. The pipe block 1 is provided with a depression or seat 5 adapted to support a pipe P, there being a gasket 6 of suitable material interposed between said seat and the lower end of said pipe, whereby the joint between said elements is rendered fluid-tight. The gasket is provided with a central opening formed therethrough which is in registration with 100

the passageway 3 and with the orifice in the toe of the pipe.

7 designates a sleeve internally threaded at its opposite ends, which sleeve is located within the opening C in the top wall of the wind chest, said sleeve being screwed at its upper end to the threaded portion 2 of the pipe block 1. The sleeve 7 is provided with a plurality of apertures 8 formed through the wall thereof. Screwed into the lower end of the sleeve 7 is a plug 9, said plug being hollow and being provided with a flange 9' adapted to contact with the lower edge of the sleeve 7. Supported by the plug 9 referred to is an electro-magnet 10 of ordinary construction, the windings of said electro-magnet, as is ordinarily the case, being arranged in electrical contact with a feed wire and a ground wire (not shown) within the wind chest A. The electro-magnet 10 is secured to the plug 9 in any convenient manner, and the core 10' of said electro-magnet is U-shaped and the upper ends thereof terminate approximately in alignment with the top edge of said plug.

11 designates the armature of the electro-magnet 10, said armature being arranged for vertical movement within the sleeve 7 at a point intermediate of the upper ends of the U-shaped core 10' and the valve seat provided at the lower end of the portion 4. The armature 11 preferably is composed of a disk of Swedish metal which is faced at its top and bottom with material such as leather or felt or any other suitable material. It will be noted by referring to Fig. 1 that the diameter of the armature 11 is only slightly less than the interior diameter of the sleeve 7 and the armature is capable of floating within the sleeve. In other words, there is no physical connection between the armature and any of the associated parts of the valve action, said armature being kept in its proper position, in so far as lateral movement is concerned, by being confined within the sleeve 7. With respect to the size of the armature, it will be noted that its diameter is much greater than the diameter of the downwardly-extended portion 4 of the pipe block 1. In other words, when the armature is located in the position suggested by dotted lines in Fig. 1, in which position the passageway 3 would be closed, there would be a space adjacent to the circumference of the armature between the top face of said armature and the bottom face of the portion 2 of the pipe block 1. 12 designates a coil spring which is interposed between the bottom face of the armature 11 and the tops of the coils of the electro-magnet 10, said coil spring being characterized by a tendency to force the armature 11 upwardly.

In the operation of a pipe organ provided with my improved valve action, the depression of a key of the organ completes an

electric circuit and thereby energies the electro-magnet 10 associated with the depressed key. The armature 11, the normal position of which is in contact with the valve seat at the bottom face of the portion 4 of the pipe block 1, is attracted and drawn downwardly by the energized magnet, and this will permit air within the wind chest A to pass through the apertures 8 in the wall of the sleeve 7 and through the passageway 3 into the pipe P, whereby said pipe will be caused to speak. In connection with the operation of an organ equipped with my improved valve actions, it is important to note that the valve action acts directly on the associated pipe; that is to say, the magnet draws the armature downwardly, thus opening the valve and permitting air to pass into the pipe instead of, as is frequently the case, operating a valve to permit air which holds the valve in a closed position to be exhausted, and in this manner, cause the valve controlling the passage of air into the pipe to be opened. It would seem that when the magnet 10 is energized and the armature 11 drawn downwardly, said magnet must overcome the pressure of the air, acting against the entire area of the lower face of the armature. This, however, is not the case, as the pressure per square inch of the air within the space between the top face of said armature and the bottom face of the portion 2 of the pipe block is the same as the pressure per square inch being exerted against the bottom face of the armature. The result of this is that the only portion of the bottom face of the armature against which air pressure is being exerted which must be overcome by the magnet is a portion of the bottom face of the armature having an area equal to the area of the bottom face of the portion 4 of the pipe block, and therefore, a smaller magnet may be employed and less electric current used than if the air pressure exerted against the entire area of the lower face of the armature had to be overcome by the magnet. A decided saving is realized because of the opportunity to use smaller electrical devices because much of the harmful sparking which would be encountered in the use of larger electrical devices is eliminated.

Fig. 3 illustrates a form of the invention in accordance with which my improved valve action is located within the toe portion of the pipe P^a. In accordance with this form of the invention, the pipe P^a is provided with a transverse wall 15 adapted to divide the toe portion of the pipe from the upper portion thereof, and said transverse wall is provided with a central opening formed therethrough. 7^a designates a sleeve which is supported in the central opening in the wall 15 and is suspended from said wall, said sleeve being provided with openings 8^a

formed in the wall thereof. The sleeve 7^a may be secured to the wall 15 in any suitable manner to produce a fluid-tight joint between these elements. As is the case in connection with the sleeve 7 shown in Fig. 1, the sleeve 7^a is provided with internal screw threads at its upper end, and 1^a designates a member which is adapted to be screwed into said upper end of said sleeve. The member 1^a is provided with a flange adapted to overlap the top edge of the sleeve 7^a and the top face of the transverse wall 15, and said member is also provided with a portion 4^a which extends downwardly from the lower face of the member and provides an annular valve seat which surrounds the lower end of the passageway 3^a formed through the member 1^a.

The lower portion of the valve action shown in Fig. 3 is constructed just as is the lower portion of the valve action shown in Fig. 1; that is to say, the hollow plug 9^a is screwed into the lower end of the sleeve 7^a, and this plug supports in any convenient manner an electro-magnet 10^a. The core of the electro-magnet is U-shaped and the upper ends thereof are arranged in approximate alignment with the top edge of the plug 9^a. 11^a designates an armature adapted for vertical movement between the valve seat formed by the portion 4^a of the member 1^a and the upper ends of the core of the magnet, and 12^a designates a coil spring which is adapted to force the armature 11^a toward the valve seat thereabove.

The valve action shown in Fig. 3 is arranged within the pipe P^a before the lower end of said pipe is secured to the upper portion thereof, and in operation, completion of the electric circuit leading to the electro-magnet 10^a will cause said magnet to be energized, thus drawing the armature 11^a away from the valve seat at the lower end of the passageway 3^a, and thus permitting air to pass through said passageway 3^a into the pipe to cause same to speak.

In Figs. 4 and 5, I show two forms of the invention which are very similar. In the operation of the valve action shown in Fig. 4, the armature 11^b is seated against the passageway 3^b in the top wall of the wind chest A^b. In other words, the lower face of the portion of the top wall of the wind chest adjacent to the passageway 3^b functions as a valve seat against which the armature is seated. In this form of the invention, the sleeve 7^b is secured to the top wall of the wind chest at the lower face thereof instead of to the pipe block as in Fig. 1.

The construction shown in Fig. 5 is exactly like that shown in Fig. 4 with the exception that the sleeve 7^c is provided with a top wall 16 having a downwardly-extended annular flange 17 which provides an annular valve seat surrounding the lower portion of the

passageway 3^c against which the armature 11^c is moved to close said passageway 3^c.

The form of the invention shown in Fig. 6 includes an element 1^d which is soldered or otherwise secured to the pipe P^d. The element 1^d is provided with a central opening 3^d formed therethrough which registers with the orifice in the toe portion of the pipe P^d and said element is provided with a downwardly-extended annular flange 4^d which surrounds the lower end of the passageway 3^d. In all other respects, the construction shown in Fig. 6 is the same as that shown in Fig. 4, the armature 11^d being movable toward and away from the valve seat formed by the annular flange 4^d to permit or prevent passage of air through the passageway 3^d.

In Fig. 7, I illustrate a form of the invention according to which the sleeve 7^e is soldered or otherwise secured to the pipe P^e instead of being secured to the top wall of the wind chest as in Fig. 6. In this form of the invention, all of the elements of the valve action are supported by the sleeve 7^e.

Throughout this specification and in some of the claims, I refer to an electro-magnet as the means for causing movement of the armature; but it is obvious, of course, that instead of an electro-magnet, I may employ a solenoid or similar electrical device for this purpose, and I do not wish, therefore, to be limited to the use of an electro-magnet.

I claim:

1. An organ comprising a wind chest, a pipe having a passageway leading thereto through which air may pass from said wind chest into said pipe, and a valve action arranged in close proximity to an end of said passageway, said valve action including a perforated sleeve, a floating valve element within said sleeve and an electrical device for causing movement of said valve element, said floating valve element being directly associated with said pipe in a manner to directly control the passage of air through said passageway and into said pipe, and the interior of said sleeve being of only slightly greater diameter than said valve element, whereby excessive lateral movement of said valve element with respect to said sleeve is prevented.

2. An organ comprising a wind chest, a pipe having an orifice in the toe portion thereof through which air may pass from the wind chest into said pipe, and a valve action arranged in close proximity to the orifice in said pipe, said valve action including a perforated sleeve, supporting means above said sleeve from which same is suspended, said supporting means being provided with a port formed therein leading directly to the orifice in the toe portion of said pipe, an electrical device at the lower end of said sleeve and an armature within

5 said sleeve, said armature being adapted to function as a closure for the port in said supporting means and being capable of being attracted by said electrical device, whereby said armature may be moved to a position where air may pass through the port in said supporting means.

- 10 3. An organ comprising a wind chest having an opening formed in a wall thereof, a pipe having an orifice in the toe portion thereof through which air may pass from the wind chest into said pipe, a pipe block provided with an air passageway formed therethrough, said pipe block being fixed to said wind chest above the opening in the wall thereof and being adapted to support the pipe, and the air passageway formed through said pipe block leading directly to the orifice in the toe portion of said pipe, and a valve action arranged in close proximity to the orifice in said pipe, said valve action including a perforated sleeve suspended from said pipe block, a valve seat located at the lower end of the passageway formed through said pipe block and at a point within said sleeve, an electrical device at the lower end of said sleeve and an armature within said sleeve, said armature being adapted to function as a closure for the passageway in said pipe block and being capable of being attracted by said electrical device away from said valve seat, whereby air may pass through the passageway in said pipe block.
- 15 4. An organ comprising a wind chest having an opening formed in a wall thereof, a pipe having an orifice in the toe portion thereof through which air may pass from the wind chest into said pipe, a pipe block provided with an air passageway formed therethrough, said pipe block being fixed to said wind chest above the opening in a wall thereof and being adapted to support the pipe, and the air passageway formed through said pipe block leading directly to the orifice in the toe portion of said pipe, and a valve action arranged in close proximity to the orifice in said pipe, said valve action including a perforated sleeve sus-
- 20 pended from said pipe block, a valve seat located at the lower end of the passageway formed through said pipe block and at a point within said sleeve, an electrical device at the lower end of said sleeve and an armature within said sleeve, said armature being adapted to function as a closure for the passageway in said pipe block and being capable of being attracted by said electrical device away from said valve seat, whereby air may pass through the passageway in said pipe block.
- 25 5. An organ comprising a wind chest having an opening formed in a wall thereof, a pipe having an orifice in the toe portion thereof through which air may pass from the wind chest into said pipe, a pipe block provided with an air passageway formed therethrough, said pipe block being fixed to said wind chest above the opening in a wall thereof and being adapted to support the pipe, and the air passageway formed through said pipe block leading directly to the orifice in the toe portion of said pipe, and a valve action arranged in close proximity to the orifice in said pipe, said valve action including a perforated sleeve sus-
- 30 pended from said pipe block, a valve seat located at the lower end of the passageway formed through said pipe block and at a point within said sleeve, an electrical device at the lower end of said sleeve and an armature within said sleeve, said armature being adapted to function as a closure for the passageway in said pipe block and being capable of being attracted by said electrical device away from said valve seat, whereby air may pass through the passageway in said pipe block.
- 35 6. An organ comprising a wind chest having an opening formed in a wall thereof, a pipe having an orifice in the toe portion thereof through which air may pass from the wind chest into said pipe, a pipe block provided with an air passageway formed therethrough, said pipe block being fixed to said wind chest above the opening in a wall thereof and being adapted to support the pipe, and the air passageway formed through said pipe block leading directly to the orifice in the toe portion of said pipe, and a valve action arranged in close proximity to the orifice in said pipe, said valve action including a perforated sleeve sus-
- 40 pended from said pipe block, a valve seat located at the lower end of the passageway formed through said pipe block and at a point within said sleeve, an electrical device at the lower end of said sleeve and an armature within said sleeve, said armature being adapted to function as a closure for the passageway in said pipe block and being capable of being attracted by said electrical device away from said valve seat, whereby air may pass through the passageway in said pipe block.
- 45 7. An organ comprising a wind chest having an opening formed in a wall thereof, a pipe having an orifice in the toe portion thereof through which air may pass from the wind chest into said pipe, a pipe block provided with an air passageway formed therethrough, said pipe block being fixed to said wind chest above the opening in a wall thereof and being adapted to support the pipe, and the air passageway formed through said pipe block leading directly to the orifice in the toe portion of said pipe, and a valve action arranged in close proximity to the orifice in said pipe, said valve action including a perforated sleeve sus-
- 50 pended from said pipe block, a valve seat located at the lower end of the passageway formed through said pipe block and at a point within said sleeve, an electrical device at the lower end of said sleeve and an armature within said sleeve, said armature being adapted to function as a closure for the passageway in said pipe block and being capable of being attracted by said electrical device away from said valve seat, whereby air may pass through the passageway in said pipe block.
- 55 8. An organ comprising a wind chest having an opening formed in a wall thereof, a pipe having an orifice in the toe portion thereof through which air may pass from the wind chest into said pipe, a pipe block provided with an air passageway formed therethrough, said pipe block being fixed to said wind chest above the opening in a wall thereof and being adapted to support the pipe, and the air passageway formed through said pipe block leading directly to the orifice in the toe portion of said pipe, and a valve action arranged in close proximity to the orifice in said pipe, said valve action including a perforated sleeve sus-
- 60 pended from said pipe block, a valve seat located at the lower end of the passageway formed through said pipe block and at a point within said sleeve, an electrical device at the lower end of said sleeve and an armature within said sleeve, said armature being adapted to function as a closure for the passageway in said pipe block and being capable of being attracted by said electrical device away from said valve seat, whereby air may pass through the passageway in said pipe block.

- 65 9. An organ comprising a wind chest, a pipe having an orifice in the toe portion thereof through which air may pass from

10 said wind chest into said pipe, and a valve action arranged in close proximity to the orifice in said pipe, said valve action including a sleeve, supporting means for said sleeve from which same is suspended, said supporting means being provided with a port formed therein leading directly to the orifice in the toe portion of said pipe, an electrical device at the lower end of said sleeve, a valve seat located adjacent to the lower end of the port formed through said supporting means, and a valve element in the form of an armature arranged for movement within said sleeve, said valve element being adapted to be moved into contact with said valve seat to prevent passage of air through the port in said supporting means and to be moved away from said valve seat by said electrical device, and the diameter of said valve element being greater than that of said valve seat, whereby air pressure from within said wind chest may be exerted against the face of said valve element opposite to the face thereof on which said electrical device acts, whereby said electrical device is aided in moving said valve element to an open position.

15 10. An organ comprising a wind chest, a sound producing device having a passageway leading directly thereto through which air may pass from said wind chest into said device, and a valve action arranged in close proximity to an end of said passageway, said valve action including a floating valve element, a guiding member for guiding said floating valve element throughout its entire stroke, and an electrical device for causing movement of said floating valve element, said floating valve element being arranged to move into open and closed positions with respect to the adjacent end of said passageway to directly control the passage of air through said device.

110 In testimony whereof, I have hereunto set my hand.

HARRY F. WATERS.
